(57) **CLAIM**

The ornamental design for a portable power supply kit, as shown and described.

DESCRIPTION

FIG. 1 is a perspective view of a power supply host showing our new design;

FIG. 2 is a perspective view viewed from another angle thereof;

FIG. 3 is a front elevation view thereof;

FIG. 4 is a rear perspective view thereof;

FIG. 5 is a left side elevation view thereof;

FIG. 6 is a right side elevation view thereof;

FIG. 7 is a top plan view thereof;

FIG. 8 is a bottom plan view thereof;

FIG. 9 is an enlarged view of the area "9" shown in FIG. 1;

FIG. 10 is an enlarged view of the area "10" shown in FIG. 1;

FIG. 11 is an enlarged view of the area "11" shown in FIG. 1;

FIG. 12 is a perspective view of a power supply showing our new design;

FIG. 13 is a perspective view viewed from another angle thereof;

FIG. 14 is a front elevation view thereof;

FIG. 15 is a rear elevation view thereof;

FIG. 16 is a left side elevation view thereof;

FIG. 17 is a right side elevation view thereof;

FIG. 18 is a top plan view thereof;

FIG. 19 is a bottom plan view thereof;

FIG. 20 is an enlarged view of the area "20" shown in FIG. 12;

FIG. 21 is an enlarged view of the area "21" shown in FIG. 12; and,

FIG. 22 is an enlarged view of the area "22" shown in FIG. 13.

The portable power supply kit is composed of a kit 1 and a kit 2, where the kit 1 is the power supply host, and the kit 2 is the power supply. The power supply host is used to charge and discharge the power supply.

The broken lines in the drawings depict portions of the power supply host that form no part of the claimed design.
